F. Holm

Shower Bath

No. 8,723

Patented Feb. 10, 1852

UNITED STATES PATENT OFFICE.

FERDINAND HOLM, OF BROOKLYN, NEW YORK.

PORTABLE SHOWER-BATH.

Specification of Letters Patent No. 8,723, dated February 10, 1852.

To all whom it may concern:

Be it known that I, FERDINAND HOLM, of Brooklyn, Kings county, State of New York, have invented a new and useful Improvement in Portable Shower-Baths; and I do hereby declare the following to be a full description of the same.

The nature of my invention consists in the combination of a force pump, with a box 10 of an octagonal or other suitable form, and jointed together at the middle so as when closed to form a semi-octagonal box to hold the force pump jets, &c., also in combining with the box or bath tub, when opened a 15 series of leaves, to extend the area of the tub, by means of slides holding the edges of the leaves together in one continuous rim to prevent the spray from the jets wetting the floor. But to describe my invention more particularly I will refer to the 20 accompanying drawings, forming a part of this schedule, the same letters in the several drawings referring to the same parts wherever they occur.

25 Figure 1 is a perspective view of the bath. Fig. 2 is a view of two of the leaves for extending the area of the tub. Fig. 3 is a view of one of the slides for holding the edges of the leaves together. Fig. 4 is a 30 plan view of the tub or box as extended showing the pins and eye pieces by which the force pump is secured to the bottom of the tub. Fig. 5 is a view of the slide piece for covering the joint of the tub or box 35 when opened. Fig. 6 is a view of the force pump and jets. Fig. 7 is a view of the box when closed, and all the fixtures of the bath are inclosed.

40 Letter A, is the box or tub. This tub is made octagonal, (though might be made of other forms, the octagonal however is preferable) and of tin or other suitable metal. In the middle of the tub, (transversely) is a joint B, so as when the bath is not wanted for use, or is to be transported to the country, the box may be closed in the smallest possible shape, as represented in Fig. 7. On the edge of the joint or hinge of the tub is a slide or covering C. The 45 use of this is to protect the joint from leaking water when the bath is being used, and also keeping the two halves of the tub from bending up. Around the edges of the tub are arranged eight leaves D, D, &c. These 50 leaves are made of metal, though oil skin or other water proof material might be used,

and are attached to the tub by means of ear pieces E, E, &c., (secured to the inner edges of the leaves,) fitting into loops or clasps F, F, &c., on the inner edges of the tub. 60 At the joining edges of these leaves, they are slightly bent over, so as to admit of the edges of the slide G, to pass underneath them and hold them firmly together and prevent any leakage of water, and thereby 65 forming, when the tub is thus put together a capacious bathing tub of simple and easy adjustment, as well as of great portability. In the bottom of this tub is arranged the force pump H, which by means of ear pieces 70 h^2 , and pins I, I, is secured to the eye pieces i^2 , i^2 , in the bottom of the tub. Connected with the force pump is an air vessel J. From the side of this air vessel, is a small pipe K, having a stop cock in it, and 75 a sprinkler on the end; also from the upper side of the air vessel is another pipe L, which is jointed for convenience of packing in the box, and has a stop cock in it, and a sprinkler on its end for showering the 80 occupant of the bath. From the side of this vertical pipe is a side pipe M, having a stop cock in it and a sprinkler to be used for the face or back as may be required. To the back of the vertical pipe is a stand- 85 ard N, for supporting the pipes, having its lower end fitting into a socket P, on the inside of the box.

Having now described my improved shower bath I will explain its operation 90 and mode of putting together. The operation of putting together is first the leaves are attached to the sides of the tub by the ear pieces in the order of their numbers, then the joining edges are secured together 95 by the slides which completes the bath tub. The next operation is to secure the force pump and jet pipes by means of the pins to the bottom of the tub. On water now being placed in the tub, the occupant of the 100 bath may force it up through either of the pipes as may be required. If for the shower, he must turn off the cocks of the two lateral pipes. If for the face or back sprinkler, he must open the upper lateral 105 stop cock, and shut off the stop cock to the showerer; or if the lower sprinkler is required, the two upper stop cocks must be shut off, thus the operator may vary the application of the water to suit his 110 pleasure.

Having now described my invention and

its operation, I will proceed to state what I claim and desire to secure by Letters Patent:

What I claim therefore, is—

5 The use of the box or tub for a portable shower bath made in two halves, in combination with the slide C, leaves D, D, &c.,

and slides G, G, &c., substantially as set forth.

FERDINAND HOLM.
